UNITED STATES PATENT OFFICE.

JOSEPH LEFLAIVE, OF ST.-ETIENNE, FRANCE, ASSIGNOR TO THE SOCIETE DES MOTEURS
SABATHIE, OF ST.-ETIENNE, FRANCE, A CORPORATION OF FRANCE.

ATOMIZER FOR LIQUID-FUEL MOTORS.

1,027,054.

Specification of Letters Patent. Patented May 21, 1912.

Application filed August 14, 1911. Serial No. 644,024.

To all whom it may concern:

Be it known that I, JOSEPH LEFLAIVE, citizen of the French Republic, residing at St.-Etienne, Department of the Loire, in

France, have invented certain new and useful Improvements in Atomizers for Liquid-Fuel Motors; and I do hereby declare the following to be a full, clear, and exact description of the invention, such as will enable others skilled in the art to which it

appertains to make and use the same.

This invention has for its object an atomizer for motors supplied with liquid fuel.

In this apparatus an outer casing fitting into the cylinder receives an inner casing containing a stuffing box and serving as a guide for a central needle which controls the admission of the jet of atomized fuel. At its lower part this needle is surrounded by an atomizing sleeve which is mounted in the inner guide box and comprises at its base slots for the passage of the fuel and upon its inner wall slots serving for the admission of compressed air.

In the accompanying drawing Figure 1 is a longitudinal section of a device embodying the invention. Fig. 2 is an underneath view of the guide casing. Fig. 3 is a sectional view of the atomizing sleeve. Fig. 30 illustrates a modification.

The atomizer in accordance with the invention comprises an outer casing 1 comprising a socket 2 for the admission of compressed air and a socket 3 for the supply of liquid fuel. The socket 3 communicates with a longitudinal passage 9 which is connected with the interior of the casing 1 by an opening 19.

Internally the casing 1 constitutes a cup 12 presenting an opening 22 upon which the needle 5 bears: this needle is controlled by an appropriate distributing mechanism and regulates the admission of fuel to the cylinder. A cap 21 is screwed to the casing 1 and at its center comprises radiating apertures 17.

The casing 1 contains an inner casing 4 which serves to guide the needle 5 and contains its stuffing-box. The lower part of this casing is guided and centered upon the inner wall of the casing 1. It presents a channel 18 through which the liquid supplied through the opening 19 enters. The part 4 comprises perforations 10 which widen out at their lower part at 11 and com-

municate through openings 8 with the channel 18. The fuel to be atomized is thus subjected to a pressure equal to that of the injecting air.

A housing 23 formed in the part 4 contains an atomizing sleeve 6 surrounding the needle 5 and applied by a spring 7 to the cup 12 of the casing 1 in such a manner as to permit of unequal expansions of the several parts.

In order to conduct the compressed air into the chamber 23 the part 4 is provided with a certain number of perforations 24. On its inner wall the sleeve 6 presents a number of slots 14 for the passage of the air and at its upper part slots 15 intended for the passage of the liquid fuel. The slots 14 and 15 do not necessarily present the form shown in the drawing but may present any suitable form.

The device acts in the following manner. At its lower part the casing 1 contains a certain quantity of fuel upon which the pressure of the injection air entering through the openings 10 and 11 is exerted. When the needle rises, it uncovers the slots 14 and 15 simultaneously. The fuel at once flows immediately through the slots 15 while the air coming from the jet 2 and conducted through the apertures 24 into the chamber 23 passes through the slots 14 below the needle 5. Owing to the tangential arrangement of the slots 15 an eddying sheet of fuel is formed in the opening 22 and the air projected through the slots 14 divides the sheet and atomizes it. The jet of atomized fuel escapes through the openings 17.

Fig. 4 shows a slightly different constructional form of the atomizing sleeve. This sleeve, instead of presenting longitudinal slots 14 internally is formed with a smooth wall but is mounted on the needle 5 with sufficient play to permit of the passage of the injection air.

In the atomizer which forms the object of the invention contact between the atomizer fuel and the walls of the apparatus is avoided by producing the atomizing in as close proximity as possible to the lower part of the needle so that the fuel has only a very short path to traverse before it enters the driving cylinder: this insures perfect combustion and high efficiency. The ratio between the volumes of fuel and air introduced is equal to the ratio between the free

sections of the slots 14 and 15. This ratio remains constant during the entire period of the lift of the needle: this condition is highly advantageous from the point of view 5 of the combustion. The atomizing of the fuel being perfect from the commencement of the opening of the needle, the same applies to the combustion which proceeds in proportion as the fuel is introduced. Any 10 desired law of combustion can be realized, this law depending upon the form of the part which controls the opening of the needle.

This arrangement presents the further 15 advantage of being exceedingly simple in construction and very easily taken apart: it also permits of unequal expansion of the several parts.

I claim:

- 20 1. The combination in an atomizer provided with an inner and outer casing, an aperture in the outer casing and a needle to co-operate therewith, of passages in said casings adapted to conduct oil to the aperture, a second set of passages independent of the first set adapted to conduct compressed air to the aperture, and a passage adapted to allow the compressed air to act on the oil to force it toward the aperture.
- 25 2. In an atomizer, an outer casing provided with an aperture, an inner casing, a needle to co-operate with said aperture carried by said inner casing, passages in the outer casing, passages in the inner casing

coöperating with the first named passages 35 to conduct the oil to the aperture, a second set of passages in the inner casing and a clearance between the casings to coöperate with said second set of passages to conduct compressed air to the said aperture, passages connecting the said clearance with the said oil passages to allow the compressed air to exert a pressure on the oil to force it toward the aperture.

3. In an atomizer, an outer casing provided with an aperture, an inner casing, a needle carried by said inner casing adapted to close said aperture, passages in said casings, an oil chamber between said casings adjacent the aperture, passages in said casings adapted to conduct oil to said chamber, passages substantially at right angles to the axis of the atomizer to conduct the oil from said chamber to the aperture, an air chamber in said inner casing, means to conduct 45 compressed air to said chamber, passages substantially parallel to the longitudinal axis of the atomizer and adjacent the needle to conduct the air from said air chamber to the aperture, and means to exert a pressure on the oil in said oil chamber.

In testimony whereof I affix my signature, in presence of two witnesses.

JOSEPH LEFLAIVE.
